(57) **CLAIM**

The ornamental design for a light fixture with optical element, as shown and described.

DESCRIPTION

FIG. 1 includes a top exploded isometric view of a light fixture with optical element.

FIG. 2 includes a bottom exploded isometric view of the light fixture with optical element of FIG. 1.

FIG. 3 includes a front exploded view of the light fixture with optical element of FIG. 1.

FIG. 4 includes a rear exploded view of the light fixture with optical element of FIG. 1.

FIG. 5 includes a left side exploded view of the light fixture with optical element of FIG. 1.

FIG. 6 includes a right side exploded view of the light fixture with optical element of FIG. 1.

FIG. 7 includes a top isometric view of the light fixture with optical element of FIG. 1.

FIG. 8 includes a bottom view of the light fixture with optical element of FIG. 1.

FIG. 9 includes a top view of the light fixture with optical element of FIG. 1.

FIG. 10 includes a front view of the light fixture with optical element of FIG. 1.

FIG. 11 includes a rear view of the light fixture with optical element of FIG. 1.

FIG. 12 includes a left side view of the light fixture with optical element of FIG. 1.

FIG. 13 includes a right side view of the light fixture with optical element of FIG. 1.

FIG. 14 includes an enlarged detailed view of region 14 of FIG. 2.

FIG. 15 includes an enlarged detailed view of region 15 of FIG. 1.

FIG. 16 includes an enlarged detailed view of view 16-16 of FIG. 3.

FIG. 17 includes an enlarged detailed view of region 17 of FIG. 9.

(Continued)

FIG. 18 includes an enlarged detailed view of region 18 of FIG. 3

FIG. 19 includes an enlarged detailed view of region 19 of FIG. 4

FIG. 20 includes an enlarged detailed view of region 20 of FIG. 5; and,

FIG. 21 includes an enlarged detailed view of region 21 of FIG. 6.

The dash-dash broken lines shown in the drawings illustrate portions of the light fixture with optical element that form no part of the claimed design. The dash-dot-dash broken line defines the boundary of the detailed view and form no part of the claimed design.
